UNITED STATES PATENT OFFICE

EDWARD C. KLINE, OF STREATOR, ILLINOIS

STEAM BOILER

Application filed August 17, 1929. Serial No. 386,517.

My invention relates to boilers and particularly to boilers of the type designed for imparting heat to a fluid such, for example, as water, while the fluid is being circulated or passed through the device.

One object of the present invention is to provide a boiler of high thermal efficiency, and which is capable of transferring a large number of heat units to a large quantity of fluid per unit of time.

Another object of the invention is to provide a construction and arrangement whereby the flow of fluid through the device is materially accelerated.

Another object of the invention is to provide, in combination with other features, a device of maximum efficiency which will occupy a minimum of space.

A further object of the invention is to provide improved spacing means between certain portions of the device.

A still further object of the invention is to improve devices of the character disclosed in sundry details hereinafter described and particularly pointed out in the appended claims.

One embodiment of the present invention is shown for illustrative purposes in the accompanying drawings in which

Fig. 1 is a longitudinal sectional elevational view through a boiler illustrating an embodiment of the present invention, and taken substantially as indicated by the line 1—1 of Fig. 2;

Fig. 2 is a transverse sectional elevational view taken substantially as indicated by the line 2—2 of Fig. 1;

Fig. 3 is a sectional plan view taken substantially as indicated by the line 3—3 of Fig. 1; and

Fig. 4 is an enlarged fragmentary sectional elevational view of a portion of the structure shown in Figs. 1, 2 and 3.

In the illustrative embodiment of the invention shown in the drawings, the boiler, designated as a whole by the numeral 10, comprises a setting 11 of brick or other suitable material in which is suitably positioned a fire box or ash pit 12 and a flue or conduit 13 by which the gases of combustion may be carried to a stack or chimney (not shown).

Mounted in the setting 11, preferably to the rear of the fire box 12, is a return header or mud drum 14 having an aperture 15 formed on its upper side and adapted to communicate with a vertically disposed nipple 16, the upper end of which is adapted to communicate with the lowermost one of a series of hollow water baffles 17, 18, 19 and 20 spaced apart from each other and suitably mounted in the setting 11 in staggered relationship with respect to each other, the alternate baffles being positioned adjacent one of the end walls of the setting and terminating short of the opposite end wall in a manner to form a circuitous passage through the setting for conducting the gases of combustion from the fire box 12 to the flue or conduit 13.

It will be noted, in the present construction illustrated in the drawings, that the front end portions of the baffles 17 and 19 are positioned adjacent the front end wall of the setting and terminate a substantial distance short of the rear wall of the setting, and that the rear end portions of the baffles 18 and 20 are positioned adjacent the rear end wall of the setting 11 and terminate a substantial distance short of the front end wall, thereby causing the gases of combustion, in their passage from the fire box 12 to the flue or conduit 13, to follow a course along the upper and lower sides of the baffles as indicated by the arrows in Fig. 1.

Positioned preferably adjacent the upper portion of the setting 11 is a steam dome 21 with which, in the present instance, the uppermost baffle 20 is adapted to communicate.

For establishing free and unrestricted communication between adjacent baffles and the steam dome, a plurality of fluid conducting nipples 22, 23, 24 and 25 are provided, the said nipples being adapted to register with apertures 26 formed in the upper and lower walls of adjacent baffles and having an area substantially equal to the cross sectional area of the nipples, the nipple 25 being adapted to register with the aperture 26 formed in the upper wall of the baffle 20 and with an aperture 27 formed in the lower wall or bottom of the steam dome 21, preferably adjacent

one end thereof. These nipples not only serve to conduct the fluid from one baffle to another, but serve also to space the baffles with respect to each other.

8 For spacing the baffles at their opposite end portions from the nipples 22, 23, 24 and 25 are a plurality of fluid conducting spacers or nipples 28, 29, 30 and 31 having means associated therewith in the form of relatively 10 small apertures 32 formed in adjacent baffles and adapted to register with the opening in the nipples 28, 29, 30 and 31, the steam dome 21 being provided with a relatively small aperture 33 adapted to register with 15 the opening in the nipple 31 in a manner to permit a restricted flow of fluid from the baffle 20 through the nipple 31 to the steam dome.

20 For establishing direct communication between the steam dome 21 and header or drum 14, and providing for circulation of the fluid through the boiler, a plurality of overflow or return pipes or conduits indicated by the numeral 34 and shown in the present instance as positioned outside the setting 11, are adapted to communicate at their upper 25 end portions with apertures formed in the lower wall or bottom of the steam dome 21, preferably adjacent the end portion of the dome remote from the aperture 27, and at 30 their lower end portions with the header 14.

It will be observed from the foregoing description that the present invention provides a structure wherein a large number of heating 35 units are transferred to a large quantity of fluid per unit of time, thereby materially accelerating a flow of fluid through the boiler, and wherein the fluid is caused to traverse substantially the entire length of the steam dome in its circulation through the device.

The embodiment of the invention shown in Fig. 1 illustrates its application to a steam heating system herein the steam generated in the dome 21 is conducted through a main 40 pipe 35 to any number of branch pipes 36, one of which is shown in Fig. 1 as communicating with one end of a steam coil radiator 37, the opposite end of the radiator being connected to a return pipe 38 by which fluid, 45 due to condensation of the steam in the radiator 37, is returned to the header or drum 14.

It will be noted that the flow of the fluid from the header 14 is unrestricted and is forced to follow a circuitous course in its 50 passage to the steam dome. The header being connected to the baffle 17 by the nipple 16, the fluid is forced therethrough, thence longitudinally of the baffle 17 in a thin broad film 55 to the nipple 22, thence through the baffles 18, 19 and 20 by way of the nipples 23, 24 and 25 into the steam dome, and thence back through the conduits 34 to the header 14, the water level in the steam dome being 60 preferably maintained at substantially the line 65 indicated by the numeral 39 in Fig. 1. Thus, it will be seen that by passing the fluid through the boiler in the manner above described, a large quantity of fluid is subjected to the heat of the gases of combustion, the 70 fluid absorbing a maximum of the heat units and accelerating the flow and circulation of fluid through the device. In the circulation of the fluid through the boiler, a relatively small portion of the fluid will pass through 75 the spacing nipples 28, 29, 30 and 31 by reason of the relatively small apertures 32 communicating therewith, thereby avoiding the burning out of the spacers and assisting, by reason of the heat absorbed in the relatively slow passage of the fluid through the spacing nipples, in accelerating the flow of fluid through the device.

When features of the present invention are adapted for use in conjunction with a two pipe steam heating system, such as shown in Fig. 1 of the drawings, not only is a rapid circulation and heating of the fluid in the boiler obtained, but the circulation of steam through the heat radiating coils of a radiator, such as 37, is materially increased by reason of a partial vacuum formed in the return pipe 38 by the rapid circulation of the fluid through the boiler elements and mud drum or header 14, creating a suction at the discharge end of the return pipe 38 and thereby greatly increasing the efficiency of such a system.

It will be observed that by reason of the rapid circulation of the fluid through the boiler, that little or practically no scale will have an opportunity to form on the interior of the baffles and fluid conducting nipples.

For supplying fluid to the system, a supply pipe 40 may be provided and adapted to communicate with the header 14, as indicated in Figs. 2 and 3, the pipe 40 being provided with a valve 41 for controlling the passage of fluid therethrough.

For determining the fluid level in the steam dome 21 a water glass 42 may be positioned outside the setting 11 adjacent the upper portion thereof and connected by means of the pipe 43 with the hollow baffle 20, and by a pipe 44 with the steam main 35.

If desired, the hollow baffles may be provided with tie bolts 45 for resisting the pressure created within the baffles, and the steam dome 21 may be provided with suitably positioned horizontally and vertically disposed tie bolts 46 and 47, respectively, for resisting the pressure generated therein.

A structure which has been found to be very efficient in its operation is one wherein elements of substantially the following dimensions have been employed. The header or mud drum 14 may be of any suitable diameter or length, depending upon the size of the setting, while the nipple 16 is preferably of approximately two and one-half 125

inches in diameter. In the structure under consideration any desirable number of water baffles may be used, the baffles contemplated being approximately six feet in length, two feet in width and one and three-quarters inches deep, connected together and spaced approximately six inches apart by fluid conducting nipples of approximately six inches in diameter, the apertures 32 formed in the water baffles and communicating with certain of the nipples, and the aperture 33 of the steam dome being approximately three-quarters of an inch in diameter, while return pipes such as 34 of approximately 2" in diameter have been found to be very desirable in a structure employing elements of approximately the relative dimensions above noted. A steam dome of approximately six feet in length, two feet in width and having a dome shaped top portion of approximately one foot in height has been found very efficient by maintaining the depth of the water in the dome at between approximately four and five inches.

When steam is up, it has been found that a boiler of the approximate relative dimensions above noted, and constructed in the manner described will cause a complete circulation of the water therethrough once every minute, thereby keeping the water-passages substantially free from the accumulation of scale, and obtaining the maximum of heat from the gases of combustion in their passage along both the lower and upper sides of the baffles and along the lower side of the steam dome 21.

A boiler embodying the features described and approximate relative dimensions of elements above noted has been in actual operation for some time, but obviously the relative dimensions noted may be varied according to the size and capacity of the boiler desired, and the requirements of the purpose for which it is to be used.

It will be observed from the foregoing description that the present invention provides a boiler of high thermal efficiency, capable of transferring a large number of heat units to a large quantity of fluid passing therethrough, and in which the flow of fluid through the device is materially accelerated. Furthermore, that a maximum of efficiency may be obtained from a boiler constructed in the manner described and occupying a minimum of space.

Obviously, the present invention is not limited to the precise construction and arrangement shown and described, as the same may be variously modified. Moreover, all the features of the invention need not be used conjointly as the same may be used to advantage in variously different combinations and subcombinations.

What I claim as new and desire to secure by Letters Patent is:

1. In a boiler, the combination of a plurality of hollow baffles and fluid conducting nipples of substantially uniform cross sectional area positioned between said baffles adjacent opposite ends thereof, the adjacent walls of adjacent baffles being provided adjacent one of said nipples with apertures of an area substantially equal to the cross sectional areas of said nipples and adapted to register therewith, said walls being also provided with relatively small apertures adjacent the other of said nipples and adapted to register with said other nipples. 70

2. In a boiler, the combination of a header, a steam dome, a plurality of hollow baffles positioned between said header and dome, said baffles having apertures of various cross sectional areas formed in their wall portions, means for operatively connecting said header and dome respectively with adjacent baffles, means adjacent opposite ends of said baffles and positioned to register with said apertures for establishing communication between the interior of adjacent baffles, and means for connecting said dome and header. 80

3. In a boiler, the combination of a header, a steam dome, a plurality of hollow baffles positioned between said header and dome, fluid conducting means for operatively connecting said header with an adjacent baffle, fluid conducting nipples positioned between adjacent baffles adjacent opposite ends thereof, the adjacent walls of said baffles being provided adjacent one of said nipples with apertures of an area substantially equal to the cross sectional area of said one of said nipples and adapted to register therewith, said walls being also provided adjacent the other of said nipples with apertures of relatively smaller area and adapted to register with said other nipple, fluid conducting nipples positioned between said dome and an adjacent baffle, said dome having apertures of relatively different size formed in one of its wall portions and adapted to register respectively with said last mentioned nipples, and a conduit for operatively connecting said dome and header. 100

4. In a boiler, the combination of a setting, a header, a steam dome mounted in said setting, a plurality of hollow baffles between said header and dome and positioned in the setting in staggered overlapping relationship with respect to each other in a manner to form a circuitous passage for the gases of combustion through said setting, fluid conducting means for operatively connecting said header with an adjacent baffle, fluid conducting nipples positioned between adjacent baffles adjacent opposite ends thereof, the adjacent walls of said baffles being provided adjacent one of said nipples with apertures of an area substantially equal to the cross sectional area of said one of said nipples and adapted to register therewith, said 120

walls being also provided adjacent the other of said nipples with apertures of relatively smaller area and adapted to register with said other nipple, fluid conducting nipples positioned between said dome and an adjacent baffle, said dome having apertures of relatively different size formed in one of its wall portions adjacent the ends thereof and adapted to register respectively with said last mentioned nipples, and a conduit outside said setting and operatively connected with said dome and header.

5. In a boiler, the combination of a setting, a header, a steam dome mounted in said setting, a plurality of hollow baffles between said header and dome and positioned in the setting in staggered overlapping relationship with respect to each other in a manner to form a circuitous passage for the gases 10 of combustion through said setting, fluid conducting means for operatively connecting said header with an adjacent baffle, and fluid conducting nipples adjacent opposite ends of said baffles communicating with the 15 interior of adjacent baffles and said dome, certain of said nipples having means associated therewith and adapted to remain in fixed relationship with respect thereto under all degrees of pressure for restricting 20 the flow of fluid through said last mentioned nipples.

6. In a boiler, the combination of a setting, a header, a steam dome, a plurality of hollow baffles having apertures of various cross sectional areas formed therein and positioned 25 between said header and dome, fluid conducting means for operatively connecting said header with an adjacent baffle, fluid conducting nipples adjacent opposite ends of 30 said baffles and communicating with said apertures and the interior of adjacent baffles and with said dome, certain of said nipples communicating with the apertures of 35 lesser cross sectional area for restricting the 40 flow of fluid through said last mentioned nipples and means outside said setting for operatively connecting said dome directly to said header.

In witness whereof, I hereunto subscribe 45 my name this 5th day of August A. D., 1929.

EDWARD C. KLINE.
